UNITED STATES PATENT OFFICE.

ALEXANDER STEWART OF PHILADELPHIA, PENNSYLVANIA.

DESIGN FOR A VENDING-MACHINE CASING.

No. 39,487.

Specification for Design.

Patented Sept. 1, 1908.

Application filed November 5, 1907. Serial No. 400,890. Term of patent 3½ years.

To all whom it may concern:

Be it known that I, ALEXANDER STEWART, a citizen of the United States, residing at Philadelphia, county of Philadelphia, and State of Pennsylvania, whose post - office address is northeast corner of Eighth and Vine streets, Philadelphia, Pennsylvania, have invented a new, original, and ornamental Design for Vending-Machine Casings, of which the following is a specification, reference being had to the accompanying drawing, forming a part thereof.

The figure is a front view of a vending machine casing showing my new design.

The design embodies a casing having an ornamental molding at its base, and a back plate which rises upwardly from the rear of

the casing, the back plate being curved at its top. A circular plate seats on the top of the casing and carries a body of cylindrical form having a semi-spherical closed upper end and a contracted mouth. A bracket is secured to the front side of the casing and has arms between which a cup is secured.

I claim

The ornamental design for vending machine casing, as shown and described.

In testimony whereof, I have hereunto affixed my signature in the presence of two subscribing witnesses.

ALEXANDER STEWART.
